Inventor:
Cyrus, H. Hardy

CYRUS H. HARDY, OF BATH, MAINE.

Letters Patent No. 89,218, dated April 20, 1869.

IMPROVED KNIFE-CLEANER

The Schedule referred to in these Letters Patent and making part of the same.

To all whom it may concern:

Be it known that I, CYRUS H. HARDY, of Bath, in the county of Sagadahoc, and State of Maine, have invented certain new and useful Improvements in Knife-Cleaners, of which the following is a full, clear, and exact description, reference being had to the accompanying drawings, making part of this specification, in which—

Figure 1 is a side elevation of my improved knife-cleaner.

Figure 2 is an end elevation of the same.

Figure 3 is a longitudinal section through the centre of the same.

This invention relates to that class of knife-cleaners in which the knife is reciprocated between a stationary and movable rubber, which form jaws to receive it; and consists in pivoting the movable jaw to a lever, so that the rubbing-surfaces will always conform to each other when worn away at either end, and also conform to the shape of the knife being cleaned, whether it is flat and of uniform thickness, or wedge-shaped in cross-section, thereby enabling the machine to perform its work in a thorough and effectual manner; and

My invention also consists in certain details, which will be particularly described hereafter.

To enable others skilled in the art to understand and use my invention, I will proceed to describe the manner in which I have carried it out.

In the said drawings—

A represents the base of the machine, which is composed of two parallel bars, *a*, and a cross-piece, *b*, from which descends a bent arm, *B*, which serves, with a thumb-screw, *c*, to clamp the apparatus to a table, or other suitable support.

C are curved arms, which rise from opposite sides of the cross-piece *b*, and serve to support the upper, or stationary jaw *D*, in which is fitted a piece of cork, *E*, a similar piece of cork, *G*, being secured to the movable jaw *H*, which is pivoted to the extremity of a handle, or lever, *I*, pivoted at *d* to the base *A*.

The pieces of cork, *E G*, thus form rubbers, between which the knife to be cleaned, or polished, is reciprocated quickly, a suitable gritty substance being em-

ployed in the operation, and the lever *I* being depressed by the hand so as to bring the surfaces of the rubbers into close contact with the sides of the knife, the back of which rests against the projections *e*, which rise above the upper edge of the cork *G*, and thus form a guard to steady the knife as it is moved back and forth.

By thus pivoting the movable jaw *H* to a lever, *I*, which is pivoted to the frame-work, instead of securing it rigidly to a lever, as heretofore, the rubbing-surfaces will be always in contact with the sides of the knife, while being cleaned, whether it is flat and of uniform thickness, or wedge-shaped in cross-section, thus enabling the machine to perform its work in a thorough and effective manner; and it will also be seen that the movement of the lower jaw will also compensate for any wearing away of the surfaces of the rubbers at either end, and cause them to fit each other at all times, as required, while, by pivoting the handle *I* to the frame-work, as above described, a leverage is obtained, so that a slight pressure only is required in operating the machine.

f are arms, which project from the movable jaw *H*, and fit between the curved arms *C*, which thus serve as guides to steady the jaw *H*, and keep it in place while the knife is being cleaned.

The jaws *D H* are each provided with lips, or flanges, *g*, which serve to hold the corks, or rubbers *E G* firmly in place, but yet allow of their being easily removed and replaced by others when worn out, and these rubbers *E G*, instead of being of cork, may, if desired, be formed of some other suitable material.

Claim.

What I claim as my invention, and desire to secure by Letters Patent, is—

The movable jaw *G*, pivoted on the short arm of the lever *I*, and furnished with lugs, *f*, to guide it in the grooves of frame *C*, substantially as set forth.

CYRUS H. HARDY.
